MARION McDONALD HANKINS, OF VANDALIA, ILLINOIS.

Letters Patent No. 70,837, dated November 12, 1867.

IMPROVEMENT IN LOOMS.

The Schedule referred to in these Letters Patent and making part of the same.

TO ALL WHOM IT MAY CONCERN:

Be it known that I, MARION McDONALD HANKINS, of Vandalia, in the county of Fayette, and State of Illinois, have invented certain new and useful improvements on Hand-Looms, of which the following is a full, clear, and exact description, reference being had to the accompanying drawing, making part of this specification, and in which—

Figure 1 represents a front view of a hand-loom constructed according to my invention, a portion thereof being in section.

Figure 2, a vertical section of the same in a plane or planes parallel to fig. 1, and

Figure 3 a plan of the treadle-motion for operating the harness detached.

Similar letters of reference indicate corresponding parts.

The nature of my invention consists, firstly, in a novel combination of straps and rollers for operating the pickers by the action of the lay; also of springs or their equivalents, in combination with picker-levers and lay of the loom, for said purpose; likewise, in such connection, a combination of levers and picker, connecting straps, rollers, pickers, and check-straps to the latter; and said invention further consists in a novel combination of rods, levers, shaft, springs, and clutch for operating the treadles which give motion to the harness; and, furthermore, in a combination or novel arrangement of harness, suspension-roller, and pulleys, and straps for operation of the harness, as hereinafter described.

Referring to the accompanying drawing, A is the lay, connected with which are picker-levers B B, hung on fulcra as at a a. Attached to the lay are straps C C, connecting the same with the picker-levers, said straps being made fast at their one end to the inner ends of the picker-levers B B, and passed over a roller, D, carried by the lay, from thence round a roller, E, attached to the breast-beam V, and back under the roller D, and made fast at their opposite ends to the lay. Rubber or other springs, F F, or their equivalents, connect the levers B B with the lay on the opposite sides of the fulcra a a, to which are arranged the straps C C, the object of which will be hereinafter referred to. H H are the pickers, attached by straps G G to the levers B B, said straps passing over pulleys b, and the pickers being further connected by check-straps I I to the ends of the shuttle-boxes.

The operation of this portion of the loom is as follows: The loom is driven by taking hold of the cap of the lay A, which in moving backwards throws the shuttle by means of the levers B B, straps C C, and picker-straps G G, driving the pickers H H. The arrangement of the roller D, or its attachment to the lay, and of the roller E, or its attachment to the breast-beam V and straps C C passing over said rollers, and from thence back to the lay, secures or holds said straps, so that the backward motion of the lay gives to the levers B B double the speed of the lay, which secures great ease and speed to the shuttle in its throw. The springs F F serve, firstly, to hold the levers B B, so that the straps C C will have what may be termed full pick on the levers B B; and, secondly, they assist the shuttle in driving back the pickers to the rear ends of the shuttle-boxes. The pulleys b under the shuttle-boxes merely serve to keep the straps G G in place, while the check-straps I I, attached to the ends of the pickers and shuttle-boxes, answer to retain the pickers to their range or extent of action in throw of the shuttle. Operated also by the lay A, or the rocking-arms or levers which carry it, are rods J J, connecting the lay with levers K K for giving a vibratory or oscillating movement to a shaft, L. This shaft carries an arm or lever, M, which has secured to its inner face a spring, N, that is connected by a rod, O, with a lever, P, of a clutch, Q, a spring, R, serving to hold said lever and clutch in place, or latter in gear with the treadle-roller T, that is restricted to motion in one direction, or from turning back, by a spring, U.

In the operation of this portion of the loom the rods J J communicate from the lay the necessary motion to the harness W, through the shaft L, spring N, lever P, clutch Q, and treadle-roller T. The spring N, to which the rod O is attached, is introduced for the purpose of allowing the lay to move forwards after the clutch Q is arrested by the lever P, striking a stop or pin, c, that insures a proper motion to the treadle-roller, irrespective of an excessive forward movement of the lay. The harness may be adjusted from one twill to another by changing the position of the pins in the treadle-roller that actuate the treadles S S, as unnecessary here to describe. The harness W is suspended by cords passing over pulleys or blocks d d d d, connected by straps Z Z Z Z to the harness-roller X, which is of varying configuration, being of larger diameter where the straps

carrying the back harness are attached, for the purpose of giving the latter the requisite motion to "shed" equally with the front harness.

The remaining details of the loom being common or well known, and not necessary here to describe in illustration of my improvement, no special reference will here be made to the same.

What I claim as new and useful herein, and desire to secure by Letters Patent, is—

1. The combination of the straps C C and rollers D E, for operation substantially as specified, to work the pickers by the action of the lay.
2. The arrangement of the picker-levers B B, constructed as described, springs F, or their equivalents, and the lay, substantially as herein set forth.
3. In combination with the levers B B, the connecting-straps G G, rollers 6, pickers H H, and check-straps I I, for operation with each other and the lay, as shown and described.
4. The means, substantially as herein described, for operating the treadle-roller T, consisting of rods J J, lever K, shaft L, spring N, rod O, and clutch and lever Q P, essentially as specified.

MARION McDONALD HANKINS.
